UNITED STATES PATENT OFFICE.

JOHANN SCHUETTE, OF ZEESEN-KOENIGS-WUSTERHAUSEN, NEAR BERLIN, GERMANY,
ASSIGNOR, BY MESNE ASSIGNMENTS, TO AMERICAN INVESTIGATION CORPORATION,
OF NEW YORK, N. Y., A CORPORATION OF MARYLAND.

AIRSHIP.

1,420,865.

Specification of Letters Patent. Patented June 27, 1922.

Application filed April 25, 1919. Serial No. 292,766.

To all whom it may concern:

Be it known that I, JOHANN SCHUETTE, engineer, citizen of the German Republic, residing at Zeesen-Koenigs-Wusterhausen, 5 near Berlin, Germany, have invented certain new and useful Improvements in Airships (for which I filed an application for patent in Germany September 12th, 1913, patent allowed under No. 301,647), of which the 10 following is a specification.

The present invention relates to improvements in ties for air-ships with a rigid frame work, according to which the said ties transect the body of the air-ships and stay 15 the framework, thereby at the same time reducing the strain on the cover thereof or the envelope of the framework. With the heretofore known tie-arrangements the ties are so disposed as to act in the vertical plane, 20 that is at right angles to the longitudinal axis of the air-ship. If, in such an air-ship one of the gas-chambers, which are disposed side by side should become empty in consequence of a defect in the envelope, or should 25 even not be filled to the same degree as the other chambers, considerable side pressures will ensue, which will act on the transverse ties of the frame work, disposed between the gas cells. By these side pressures acting 30 upon them, the said transverse ties are subjected to very severe stresses, whereby the thrust is transferred to the frame work itself, which may even lead to the fracture of some of the beams of the frame work.

35 This disadvantage is obviated according to the present invention by ties being also disposed in the longitudinal direction of the airships in such a manner that they are coupled both to the end walls of the gas cells 40 and to the transverse ties of the frame work.

In the accompanying drawing the invention is exemplified in an embodiment employed in an airship with transverse frame rings tied by wires. Figs. 1, 2, and 3 show 45 an arrangement for a frame work with radial tie wires meeting at a central crossing point in the longitudinal axis, while Fig. 4 shows a modification, according to which the tie wires of the frame rings cross each 50 other at several points.

In both modifications the crossing points of the tie wires *s* of the frame rings *r* are

coupled by tractive members *c* which are carried through the different gas cells.

In the arrangement according to Figs. 1, 55 2, and 3, in which the transverse tie wires *a* meet in a central point in the longitudinal axis, there is provided only one such longitudinal tie wire *c* extending along the said longitudinal axis of the airship, whereas in 60 the arrangement according to Fig. 4 the four crossing points *t¹*, *t²*, *t³*, *t⁴*, have been chosen as coupling points for the tie wires, so that here we have four longitudinal ties *c*.

In order that the envelope of the gas cells 65 may be relieved of all strain, the gas cells are provided with indentures *a¹* at the center of the end wall at the place where the longitudinal ties are attached, the indentations being preferably conical. At the crossing 70 points of the transverse tie wires *s* preferably special coupling members, such as the eye-plate *e* shown in Fig. 3, are employed. The longitudinal ties are passed through the gas cells either by means of the angles and 75 eyes disclosed in my prior Patent No. 992-909 granted May 23, 1911, or by aid of further eye-plates *h*, which are riveted to each other through the material *d* of the cells and short intermediate tie members 80 *c¹* coupling said plates *h* to the plates *e* (Fig. 3). The arrangement may, also, be such that the ties may be held taut while the gas cells are being inflated; in this case a pulley block, to be operated from below 85 is substituted for the short intermediate ties.

What I claim is:

1. In an airship the combination, with a rigid frame work, gas cells and transverse 90 ties, of longitudinal ties, coupled both to the end walls of the gas cells and to the transverse ties of the frame work.

2. In an airship, the combination with a rigid frame-work and transverse frame 95 rings, of crossed transverse tie wires by means of which the said frame rings are stayed, longitudinal ties coupled with the transverse tie wires at points where the transverse wires intersect, and gas cells with 100 indented walls, said longitudinal ties being attached to the indented walls of the said gas cells.

JOHANN SCHUETTE.
